UNITED STATES PATENT OFFICE.

FRED FULGORA, OF PITTSBURGH, PENNSYLVANIA, ASSIGNOR OF ONE-HALF TO JAMES J. CLAIR, OF PITTSBURGH, PENNSYLVANIA.

RETAINER.

1,315,768.

Specification of Letters Patent. Patented Sept. 9, 1919.

Application filed July 17, 1917. Serial No. 180,986.

To all whom it may concern:

Be it known that I, FRED FULGORA, a citizen of the United States of America, residing at Pittsburgh, county of Allegheny, 5 and State of Pennsylvania, have invented certain new and useful Improvements in Retainers, of which the following is a specification.

This invention relates to retainers, more particularly for use in the connection with a note book for detachably securing the book in the pocket of a garment to prevent accidental displacement, and although designed primarily for the purpose of a book retainer, yet it is to be understood that the device can be employed for any purpose wherein it is found applicable, and the invention has for its object to provide, in a manner as hereinafter set forth, a simple, strong, 15 durable, efficient and inexpensive retainer, for the purpose hereinbefore referred to.

With the foregoing and other objects in view the invention consists of the novel construction, combination and arrangement of parts, as hereinafter more specifically described and illustrated in the accompanying drawings, wherein is shown an embodiment of the invention, but it is to be understood that changes, variations and modifications 25 can be resorted to which come within the scope of the claim hereunto appended.

In the drawings wherein like reference characters denote corresponding parts throughout the several views.

Figure 1 is a perspective view of a note book showing the adaptation of the retainer device in accordance with this invention.

Fig. 2 is a longitudinal sectional view of one side of the cover of a book the retainer being attached to said side, further being illustrated in longitudinal section.

Fig. 3 is an elevation of the book with one side of the cover thrown back and further illustrating in connection with said side 45 showing the adaptation therein of the retainer in accordance with this invention.

Fig. 4 is a cross sectional view of a retainer.

Referring to the drawings in detail, 1 denotes the front section or side of the cover of a note book 2. The said side being flexible.

Fixedly secured to the section 1, centrally of the outer end thereof, as well as to the 55 outer face thereof, is a retainer or holder

in accordance with this invention, and which consists of a rectangular body portion 3, formed of thin metallic material, and which when secured to the outer face of the section 1 of the cover acts as a reinforcement for 60 said section and prevents the same from buckling.

Formed integral with each longitudinal edge of the body portion 3, near the outer terminus thereof is a laterally extending 65 bendable securing barb 4. Each of the bars 4 is adapted to extend through the section 1 and be clenched against the inner face of said section 1 as at 5, see Fig. 3.

Formed integral with each longitudinal 70 edge of the body portion 3, near the inner terminus thereof is a laterally extending bendable securing barb 6, and each of said barbs 6 is adapted to extend through the section 1, and be clenched against the inner 75 face of said section, as at 7, see Fig. 3.

Formed integral with the inner horizontal edge of the body portion 3, centrally thereof, is a laterally extending bendable securing barb 8, which is adapted to extend 80 through the section 1 and be clenched against the inner face of said section 1, as at 9, see Fig. 3.

The barbs 4, 6 and 8 are tapered, and each of the barbs 4, 6 is of a length, that when 85 positioned to secure the body portion 3 to the section 1, it will terminate at a point between the longitudinal center and one longitudinal edge of the body portion 3. The barb 8 is of such length, that when in securing position, it will have its free end extend between the free ends of the barbs 4, 6.

By employing the barbs at the side edges and the barb at the inner end edge of the body portion 3, the latter can be fixedly secured to the section 1.

The outer terminus of the body portion 3, merges into a clamping arm 10, which opposes the outer face of the body portion 3. The arm 10 is of tapering formation and 100 of ogee curvature in longitudinal section and substantially concave in transverse section.

The inner or free end of the arm 10, as at 11, is circular and indented as at 12.

The clamping arm 10, is resilient, and its free end is normally in close proximity to the outer face of the body portion 3, and owing to the shape of the arm, when a ply of fabric is inserted between the arm 10 and 110

the body portion 3, said inner end 11 of the arm 10 will frictionally clamp said ply of fabric, whereby the book will be prevented from accidental displacement.

5 The concaving of the arm not only reinforces it but also increases its elastic characteristic.

What I claim is:

10 A retainer for the purpose set forth comprising a flat rectangular metallic body having each longitudinal edge provided with a pair of bendable securing barbs and its inner horizontal edge with a bendable securing barb, a tapering resilient clamping arm

15 forming a continuation of the outer terminus of said body and positioned against the outer face of the latter, said arm being of ogee curvature in longitudinal section throughout and substantially concave in cross section at any point from near its forward to near its inner end, said arm having its inner end free and circular and indented.

20 In testimony whereof I affix my signature in the presence of two witnesses.

FRED FULGORI.
